UNITED STATES PATENT OFFICE.

EDWIN H. WHITNEY, OF PROVIDENCE, RHODE ISLAND, ASSIGNOR TO THE AMERICAN SHIP WINDLASS COMPANY, OF SAME PLACE.

REVERSING-GEAR FOR ENGINES.

SPECIFICATION forming part of Letters Patent No. 366,905, dated July 19, 1867.

Application filed March 22, 1867. Serial No. 231,951. (No model.)

To all whom it may concern:

Be it known that I, EDWIN H. WHITNEY, of Providence, in the county of Providence and State of Rhode Island, have invented a new and Improved Reversing-Gear for Steam-Engines, of which the following is a full, clear, and exact description.

Reference is to be had to the accompanying drawings, forming a part of this specification, in which similar letters of reference indicate corresponding parts in all the figures.

Figure 1 is a side elevation of the reversible eccentric provided with a hand-wheel for operating the same, and showing also a portion of the engine-shaft and its bearing or pillow block. Fig. 2 is a front elevation of the same, showing the engine-shaft in cross-section. Fig. 3 shows the opposite side view from that shown in Fig. 1, the hand-wheel and its hub being shown in sectional elevation. Fig. 4 is a front elevation, the same as Fig. 2, showing the shaft in section, and showing the hand-wheel turned to the left, in position to act upon the eccentric for reversing the same; and Fig. 5 is a similar view to Figs. 2 and 4, showing the hand-wheel and the eccentric as having reached their extreme reversed position.

The invention will first be described in connection with the drawings, and then pointed out in the claims.

A represents the shaft of the engine journaled in the bearing or pillow block B, and provided with the loose eccentric E, which operates the main valve of the engine. The eccentric E is formed or provided with the elongated hub h, on which is placed loosely the hand-wheel R, which has formed in the hub R' thereof the two opposite cam recesses or grooves, s s'. A pin, P, is screwed into the shaft A adjacent to the hub h of the eccentric E, (shown clearly in Fig. 3,) and the hub h is cut away to form the opposite shoulders d d', which are adapted to strike the pin P to limit the movement of the eccentric upon the shaft A in both directions. Screwed into the hub h of the eccentric E is the pin c, (shown clearly in Fig. 1,) with which the shoulders i i' of the hub R' of the hand-wheel R are adapted to engage to limit the independent movement of the

hand-wheel upon the hub h of the eccentric, and secured to the hub h of the eccentric E are the two springs g g', formed with catches a a', and provided at the catches with the laterally-projecting pins o o', which reach into the above-mentioned cam-grooves s s', made in the hub R' of the hand-wheel.

H represents the relative position of a crank-pin to the point marked k, which indicates the center of the eccentric E, which shows the proper application of the eccentric to the shaft.

The parts being in the position shown in Fig. 2, and the shaft A revolving in the direction indicated by the arrow placed thereon in said figure, the pin P strikes the shoulder d, and thus revolves the eccentric with the shaft. At this time the catch a of the spring g engages the pin P, so that the hand-wheel cannot be turned backward, and at this time also the catch a' of the spring g' will have been carried outward by the cam s' out of range of the pin P, and the shoulder i' of the hand-wheel will engage the pin c, as shown in Fig. 1. Now, to reverse the engine the hand-wheel has simply to be turned in the direction of the arrow in Fig. 4. At the outset the hand-wheel will turn independently upon the hub h of the eccentric until the shoulder i strikes the pin c. This independent movement causes cam s to lift the spring-catch a out of engagement with the pin P, and cam s' to bring the catch a' into range with the said pin P, as shown in Fig. 4. The further turning of the hand-wheel will turn the eccentric with it, in consequence of the shoulder i striking the pin c, and this will continue until the shoulder d' of the eccentric strikes the pin P, at which time the eccentric will be reversed and the shaft A caused to revolve in the opposite direction, as indicated by the arrow placed thereon in Fig. 5, and the spring-catch a' will now engage the pin P, as shown in Fig. 5.

The inner faces of the spring catches a a' are beveled, as shown, to cause them to ride over the pin P, and small clearances f f' are formed at the inner ends of the cam-recesses s s', respectively, to permit the catches to have the necessary slight radial movement to permit them to pass the said pin.

Having thus fully described my invention, I claim as new and desire to secure by Letters Patent—

1. The eccentric formed with the hub h , 5 formed with shoulders $d d'$ to engage a stop-pin on the shaft A , in combination with an operating-wheel, R , placed upon the hub of the eccentric and having a limited independent rotary motion thereon, substantially as described.
2. The eccentric E , having a limited independent motion upon the shaft A , in combination with the hand-wheel R , connected to the eccentric and having a slight rotary motion independent of the eccentric, substantially as described.
3. The eccentric E , having a limited inde-

pendent motion upon the shaft A , and a hand-wheel, R , having a rotary motion independent of the eccentric, combined with spring-catches $a a'$, arranged to lock the hand-wheel to the shaft, substantially as described.

4. The eccentric E , formed with the hub h and shoulders $d d'$, the shaft A , provided with a stop-pin, P , and the wheel R , placed upon the hub of the eccentric and formed with the shoulders $i i'$ and cams $s s'$, in combination with the spring-catches $a a'$ and the pin c , all arranged to operate substantially as described.

EDWIN H. WHITNEY.
